UNITED STATES PATENT OFFICE.

JOHN DOBBIE, OF LEITH, SCOTLAND.

DESIGN FOR A HANDLE FOR STONE-DRESSING TOOLS.

SPECIFICATION forming part of Design No. 31,283, dated July 25, 1899.

Application filed March 13, 1899. Serial No. 708,968. Term of patent 14 years.

To all whom it may concern:

Be it known that I, JOHN DOBBIE, a subject of the Queen of the United Kingdom of Great Britain and Ireland, residing at Dobbie's Wharf, Old Bridge End, Coalhill, Leith, Scotland, have invented and produced a new and original Design for a Handle for Stone-Dressing Tools, of which the following is a specification, reference being had to the accompanying drawings, forming part thereof.

In said drawings, Figure 1 is an edge elevation of a handle for stone-dressing tools, showing my new design. Fig. 2 is a longitudinal section on the line 2 2 of Fig. 3. Fig. 3 is a longitudinal section on line 3 3 of Fig. 2.

As shown in the drawings, the leading or material feature of my design for handles for stone-dressing tools consists of a bar H, laterally enlarged at one end and bifurcated at

its enlarged end to form integral jaws B B, 20 each of which jaws is formed with an angular groove or recess A in its inner face, running parallel with and occupying a position near or toward the enlarged lower extremity of the jaw, and the transverse bolt-hole C, 25 formed with the concentric tapered or countersunk recesses D D' and square recess E.

Having thus described my invention, the following is what I claim as new therein and desire to secure by Letters Patent:

The design for a handle for stone-dressing tools, substantially as herein described and shown.

JNO. DOBBIE.
